UNITED STATES PATENT OFFICE.

JOHN O. SCHMITT, OF CLEVELAND, OHIO, ASSIGNOR OF ONE-HALF TO ALBERT TREIBER,
OF CLEVELAND, OHIO.

MOTOR-BOAT CAROUSEL.

1,124,336.

Specification of Letters Patent.

Patented Jan. 12, 1915.

Application filed December 13, 1913. Serial No. 806,393.

To all whom it may concern:

Be it known that I, JOHN O. SCHMITT, a citizen of the United States, residing at Cleveland, in the county of Cuyahoga and 5 State of Ohio, have invented certain new and useful Improvements in Motor-Boat Carousels, of which the following is a specification.

This invention pertains to what is known 10 as a marine roundabout, the same comprising a series of flexibly connected vessels or boats which have the merry-go-round characteristic, all substantially as shown and described and particularly pointed out in the 15 claims.

In the accompanying drawings Figure 1, is a perspective view of my invention in one of its preferred forms shown under an open canvas or canopy. Fig. 2 is a plan view, 20 enlarged, of two boats and their operating connections with each other and the center about which the boats make their circuit. Fig. 3, is a side elevation of Fig. 2 looking in at the front and showing also the water 25 tank or channel in which the boats run. Fig. 4 is an enlarged side elevation of one of the trailing supports for the radial arms or rods which govern the boats from the center. And Fig. 5 shows a modification of 30 the means for imparting an undulating movement to the boats as they travel in their circuit.

The conception herein involves the application of the merry-go-round principle to a 35 series of boats traveling together in the water and having the action of boats out upon a lake or seat where the waves give them the rocking movements. It is sought herein to reproduce this effect with the 40 nearest possible approach to the real or natural, and thus afford a more or less exciting and exhilarating amusement for children, particularly, but under conditions wherein there is perfect safety as far as 45 danger from accident is concerned. To these several ends I employ a series of boats B, which have flexible connections 2 between them and are confined to travel about a common center C by arms or rods 3. The 50 said arms or connections 3 are radially disposed about said center or pole C and are flexible between their ends to afford rocking or undulating accommodation to the boats. Furthermore, the said arms are connected 55 directly with the extremities of the boats

by ball and socket or other free joints, and also are adapted to flex in a vertical direction at their outer ends without really affecting their inner ends, and this movement is provided by means of a double spring 60 joint D. At the said joint the links or sections constituting the said arms are pivotally connected and the opposite springs 4 are supported on their ends by the cross bar 5 rigid with said sections respectively and 65 adapted to allow the boats to toss and play without communicating their action to the trailers or trolleys E, which support said arms on the endless circular track F. The said trailers have rollers 12 which run on 70 said track F, and the inner ends of the said arms E are affixed by suitable pivot joints 7 to the spider or wheel G mounted to rotate on the pole C. It is important that the said arms should have the freest possible move- 75 ment on the pole C, and to this end I have provided said wheel with antifriction ball bearings on said pole and which is sustained thereon at a given or fixed elevation by any suitable means. 80

Power is applied to the flotilla or fleet of boats by means of an engine or motor of some suitable kind located in one or more of the boats, and for this purpose an electric motor is preferred but a gasoline or other 85 engine may be employed. A single source of power in any one of the fleet may suffice, but in that case the other boats will be given the appearance of containing power of their own by means of a dummy engine 90 or the like so as to, at least make the boats harmonize in appearance.

Now, in order to afford the undulating or wavy effect to all the boats alike, I may employ say one of two ways for this purpose. 95 Thus, in Figs. 1 and 2 I show the track F as constructed with a wavy riding surface, most clearly seen in Fig. 1, and the said arms 3 of each boat run quite close together on the wheel G and are so related and positioned where they cross said track with their respective trailers or trolleys that one trailer will come to a depression in the track F when the trailer of the other or companion arm reaches a rise or elevation in said track 100 and the said depressions and elevations are uniformly spaced apart about the entire track and correspond to the space between the arms 3 at that point. It follows that one arm of each boat is down when the other is 105 110

up on said track, and this difference is imparted to the boat through said arms, the action being gradual to begin with but soon establishing itself in the tossing movement of the boat as the unavoidable consequence of the construction and working relation of the said arms and track. The flex at D is a necessary adjunct but it does not detract from the function of the said arms in guiding the boats on their circuit. Coupling links 8 of wire or rods unite said arms at their middle. Another way of getting the more or less tossing motion of the boats is by a wave track H located in the bottom of the fluid channel or tank L directly beneath the boats and having rises and depressions successively so spaced apart that when a boat floats high at one end it will be low at the other and so on alternately around the track and with the same effect as to all the boats. In this construction a single trolley or trailer J is employed beneath the bow of each boat and runs on the said track H while the rear of the boat is perfectly free in the water. The said trailer is pivoted and swiveled on a bracket 9 on the bottom of the boat and has a spring 10 interposed between the heel thereof and the boat to exert a constant downward pressure and thus keep the trolley down on the track on all portions thereof. In this instance I employ the arms or guide rods or connections 3 the same as in Fig. 1, but these might be dispensed with and the boats put upon their individual guidance by so constructing the trolley wheel 12 and the track therefor that the wheel would be compelled to follow the track under all conditions of travel and regardless of the load. This can be accomplished by giving the said wheel 12 a deep flanged periphery of say Ω shape and a track to correspond, or the equivalent of such a construction. The connection 2 between boats would however necessarily be preserved.

What I claim is:

1. The installation described consisting of a water tank, a series of boats connected endwise and radially disposed arms adapted to guide said boats in a circle, a spring pressed supporting trolley for each arm and a circu-

lar undulating track on which said trolleys travel, said arms being flexible between their ends.

2. An amusement installation as described, comprising a water tank, a series of boats flexibly connected and a pair of arms pivoted respectively with the ends of each boat and radially disposed from the center of said tank, a rolling carrier for each arm and an undulating track on which said carriers travel, said arms extending across said track and spaced apart at said crossing so as to bring one arm into a depression and the other onto a rise of said track alternately, and connecting links uniting all said arms outside said undulating track.

3. A roundabout amusement installation comprising a water tank, a series of flexibly connected boats in said tank, a central upright and a spider free to turn thereon, radially disposed flexible arms in pairs connected with said spider and said pairs of arms connected respectively with the ends of said boats, an undulating track about said spider and apart therefrom and a trolley wheel on each arm adapted to travel on said track, the flex of said arms being outside said undulating track.

4. The installation described comprising a central post, a spider provided with anti-friction bearings rotatable on said post, a series of boats flexibly connected at their ends and a pair of radially disposed arms connected respectively with the ends of said boats and said pairs of arms each starting from the same pivot on said spider, a circular undulating track about said spider and spring pressed carriers for said several arms running on said track and supporting said arms thereon, the said undulations and arms where they cross the same being so disposed that one arm of a pair reaches a high point in an undulation when the other reaches a low point.

In testimony whereof I affix my signature in presence of two witnesses.

JOHN O. SCHMITT.
